Notice of Allowance dated Jun. 17, 2022 in U.S. Appl. No. 35/510,831.

Primary Examiner — Khawaja Anwar

(57) **CLAIM**

The ornamental design for a guitar, as shown and described.

DESCRIPTION

FIG. 1 is a front, top and right side perspective view of a guitar showing my new design;

FIG. 2 is a front, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is an enlarged right side view thereof;

FIG. 8 is an enlarged left side view thereof;

FIG. 9 is a partial enlarged view showing the bridge part thereof;

FIG. 10 is another partial enlarged view showing the bridge part thereof;

FIG. 11 is another partial enlarged view showing the bridge part thereof;

FIG. 12 is another partial enlarged view showing the bridge part thereof;

FIG. 13 is another partial enlarged view showing the bridge part thereof;

FIG. 14 is another partial enlarged view showing the bridge part thereof; and,

FIG. 15 is another partial enlarged view showing the bridge part thereof.

The broken lines illustrate portions of the guitar that form no part of the claimed design. The dash-dotted lines denote the boundary of the claim and form no part of the claimed design.

1 Claim, 15 Drawing Sheets
